UNITED STATES PATENT OFFICE.

THOMAS W. PORTER, OF TUXEDO PARK, NEW YORK, ASSIGNOR TO THE PATENT
BUTTON COMPANY, OF WATERBURY, CONNECTICUT, A CORPORATION OF CON-
NECTICUT.

BUTTON.

1,179,034.

Specification of Letters Patent. Patented Apr. 11, 1916.

Application filed May 13, 1912. Serial No. 696,929.

To all whom it may concern:

Be it known that I, THOMAS W. PORTER, a citizen of the United States, and a resident of Tuxedo Park, in the county of Orange 5 and State of New York, have made and invented certain new and useful Improvements in Buttons, of which the following is a specification.

My invention relates to an improvement 10 in buttons, and more particularly to that type or kind thereof which is employed with a staple, provided with two or more prongs, and adapted to pierce its way through the bottom of the button and turned, bent or 15 upset against a die contained within the button, the object of the invention being to provide an article of this kind which shall be cheap to manufacture and assemble, and wherein the top or face plate may be of a 20 straight or flat form without danger of being marred or injured by the upsetting of the pointed end of the prongs, and with these and other ends in view, consists in certain novel features of construction and combination of parts as will be hereinafter fully 25 described and pointed out in the claims.

In the accompanying drawings, Figure 1 is a sectional view of my improved button prior to being secured to the cloth or fabric; 30 Fig. 2 is a similar view thereof, after being secured in place; Fig. 3 is a top plan view of the button, a portion of the face plate and anvil or die being broken away; Fig. 4 is a detached perspective view of the anvil 35 or die; Fig. 5 is a similar view of the anchor; Fig. 6 is a sectional view of a modified form of the button prior to being attached to the cloth or fabric; Fig. 7 is a 40 similar view showing the button attached; Fig. 8 is a perspective view of the detached modified form of die; Fig. 9 is a similar view of the anchor; Fig. 10 is a top plan view of a modified form of the button, a portion of 45 the face plate and die being broken away for the sake of clearness; Fig. 11 is a sectional view of a modified form of the button, the anchor being made in the form of a disk and resting in the body of the button and 50 against the die; Fig. 12 is a view in perspective of the anchor employed in connection with the button as illustrated in Fig. 11; Fig. 13 shows the button in section and provided with a still further modified form of 55 anchor, the die being inclosed or incased

therein; Fig. 14 is a sectional view of the button showing the die and anchor made integral; Fig. 15 is a top plan view of the die and anchor illustrated in Fig. 13, a portion of the anchor being broken away to better 60 illustrate the die inclosed therein; and, Fig. 16 is a view in perspective of the integral anchor and die illustrated in section in Fig. 14.

Referring to the drawings, A represents 65 the body of the button, provided with the downwardly extending hub B, and with the imperforate base C, the latter being bent or formed to provide a circular groove D, said body, hub and imperforate base being preferably constructed of one piece of metal. Within the body and hub of the button is contained an anchor E shown in perspective in Fig. 5, this anchor being made in the 70 form of a shell, one end thereof being open, and the opposite end closed and bent inwardly or downwardly to form a cavity or recess e, the sides e¹ of the shell or anchor being preferably of such height or length as to permit it to be nicely contained within the button between the base thereof and the 75 die, as hereinafter explained. The edge e² of this anchor surrounding the open end thereof is contained within the recess in the imperforate base of the button formed between the hub B and the sides of the groove or recess D, as clearly illustrated in Figs. 1 and 2 of the drawing. On the upper edge e³ of the shell or anchor E, and also on the 80 body A, rests the die F, shown in perspective in Fig. 4, and constructed in the form of a disk, a recess or cavity G being thereby 85 formed between the die F and the top e of the anchor E, to receive and retain the bent 90 or upset ends of the fastening staple. Upon 95 this flat disk or die F rests the top or face plate H, the outer edge of the latter being bent over upon the body A to retain the parts in their proper relative positions. 100

With the button so constructed, is employed a staple provided with two or more prongs, that illustrated in the drawing being provided with the two prongs I formed on or secured to the base or plate K, the free 105 ends of the prongs I being pointed and adapted to pierce their way through the cloth or fabric L, the base C of the button, and the top of the anchor or shell, and bent or upset against the die or anvil F. By 110

reason of this construction and arrangement of the parts, the pointed ends of the prongs 5 I are directed into the recess D in the base of the button, and prevented thereby from slipping laterally on said base, the prongs puncturing or piercing the base, and likewise the upper plate or top of the anchor E, the recess G between said anchor and anvil plate F receiving and retaining these bent 10 or upset ends, as illustrated in Fig. 2.

As illustrated in Figs. 6-10 inclusive, the shape of the die and anchor may be slightly modified, that is, instead of being bent downwardly or inwardly to form a cavity 15 or recess at its upper end, it might be domed, in which instance the die will be so shaped as to properly spread or separate the points of the staple and bend them into the space between said die and anchor.

20 As illustrated in Fig. 9, the anchor M is shaped like that shown in Fig. 5, that is, is in the form of a shell; the lower end thereof being open, but the opposite end or top N being convex instead of concave. When 25 such a form of anchor is used, the die O illustrated in perspective in Fig. 8 will be provided with the downwardly projecting portion P employed for the purpose of directing the points of the staple Q downwardly and outwardly, as clearly illustrated 30 in Fig. 7, the bent or overturned points of the staple occupying the space between the convex top of the anchor and the under side or surface of the die or anvil.

35 By so constructing the parts, it will be understood that there is little or no danger of the piercing or pointed ends of the prongs marring or injuring the top or face plate H of the button, which, as before stated, is 40 preferably made flat; furthermore, by forming and arranging the anchor or shell as illustrated and above described, that is, with the open end thereof located in the base of the button, and the closed or anchoring end 45 thereof located in the top of the button, the necessity of providing a die extending down into the hub of the button, as has heretofore been the case, is avoided. Furthermore, the button is a neat and attractive one, cheap to 50 manufacture and assemble, and by actual test strong and capable of withstanding any strain which might be imposed upon it when in use.

55 It is to be further noted that by reason of the formation and arrangement of the several parts, the prongs of the staple are held against a rocking, tilting or twisting movement at points near the base and near the pointed ends thereof, these two points of 60 engagement, one near the lower end of the prongs, and the other near the upper end of the prongs, being so widely separated as to insure against all danger of the staple being moved or twisted from engagement 65 with the button after being secured thereto.

Furthermore, by reason of the fact that the staple pierces its way out not only through the imperforate base of the button, but also through the shell, its engagement therewith is rendered much more secure than in instances where holes or openings are provided in the base of the button or in an inserted disk, or other element contained within the same, or in both. In other words, the prongs of the staple are caused to more 70 tightly engage with two parts of the button, and at points widely separated. Again, the inner side or surface of the shell being continuous, it affords a guide to the prongs of the staple after having pierced their way through the imperforate base, and serves to properly direct them toward the closed end of the shell, avoiding any undue tilting of the same while the staple is being secured to and within the button.

85 While I prefer to construct the button as above described, yet it will be obvious to those skilled in this art that the same advantages may be secured when the button is constructed as shown, for instance, in Fig. 90 11, wherein the anchor is made in the form of a disk R extending across the body R¹ of the button and against the anvil R² provided with a central depression r for the purpose of deflecting the points of the 95 prongs R³ over and onto the anchor R. This anchor R, as illustrated in perspective in Fig. 12, will be pierced by the pointed ends of the prongs in the act of securing the 100 button to the cloth, as is the case in the anchor before described, and being widely separated from the base of the button, the same advantages will flow therefrom. Again, as illustrated in Figs. 13 and 15, the 105 anchor S may be made in the form of an inverted dome, and bent over and upon the die S¹, or, as illustrated in Figs. 14 and 16, the anchor and die may be made in one piece in the form of a shell, the lower side T acting as the anchor and the depression t in the 110 top T¹ acting as the die to deflect the piercing ends of the prongs. In all these instances, however, it will be noted that both the bottom of the button and the anchor are imperforate, the two parts being widely 115 separated, so that all danger of the button rocking or tilting on the fastener or becoming disengaged therefrom is avoided.

What I claim is:—

1. A button comprising a top plate, a 120 body, and a hollow hub with an imperforated base at the lower extremity thereof, said base provided with an annular groove spaced a distance from the outer periphery thereof, an anchor located within said hollow hub and comprising a hollow shell with the side 125 walls thereof contacting with the side walls of said hub, the open lower extremity of said shell located between the side walls of said hub, and the walls of said annular 130

groove, the upper extremity of said shell provided with an imperforated top plate with a central depression, a flat plate die interposed between the upper extremity of 5 said shell and the top plate of said button and wedgedly holding the several parts in fixed position.

2. A button comprising a top plate, a body, and a hollow cylindrical hub with an 10 imperforated base, said base provided with an annular groove spaced a distance from the outer periphery thereof, an anchor member located within said hollow cylindrical hub, and comprising a hollow cylindrical 15 shell with the side walls thereof in continuous contact with the side walls of said hub,

the lower extremity of said shell resting upon the walls of said annular groove, the upper extremity of said shell provided with an imperforated top plate, formed with a 20 central depression, a flat plate die positioned between the top plate of said button and the upper extremity of said shell, and holding the several parts in fixed position.

Signed at New York, borough of Manhattan, in the county of New York and State of New York, this 10th day of May, A. D. 1912. 25

THOMAS W. PORTER.
